UNITED STATES PATENT OFFICE.

THOMAS R. MILLS, OF WASHINGTON, DISTRICT OF COLUMBIA.

AVERAGE-SPEED-RECORDING MEANS FOR RAILWAY TRAINS.

Application filed March 19, 1926. Serial No. 96,011.

Over certain specified lengths of trackage, particularly through yards, trains are supposed to proceed at or under a predetermined speed, and when this speed is ex-

ceeded, serious accidents very often occur and it is an impossibility to determine even from eye witnesses, the speed which the train was making at the time of the accident. It is one object of my invention how-

ever, to provide a novel speed recording means which will, with extreme accuracy, record the average speed in miles per hour, of all trains moving over a short length of trackage or block, with which the invention is used.

In the operation of electrical signalling systems, it is customary to make use of signal controlling relays, which relays are controlled by track circuits, these circuits being so affected by entrance of a train into a block and departure from such block, as to cause functioning of the relays to actuate the usual signals. A further object of my invention is to provide speed recording means which may be accurately controlled by switches which are in turn controlled by the usual signal controlling relays, thus insuring that the cost of installing the invention shall be as small as possible.

While the recording means is preferably controlled by track circuits and relays, it may in some instances be controlled otherwise, for instance, by the well known "boxes" which function under the vibration of the track rails, to control an electrical circuit or circuits, or by other instruments.

In the accompanying drawing which diagrammatically illustrates one form of the invention:—

Fig. 1 is a diagram showing the normal position of a marker which is employed in connection with a recording surface, and this view illustrates the invention of a nature to be controlled by signal-actuating relays of a block signalling system.

Fig. 2 is a detail side elevation of the driven support for the recording surface, the surface marker, and associated parts.

Fig. 3 is a view similar to a portion of Fig. 1 but illustrating a different form of recording surface, the latter being upon a tape in this figure, whereas it is upon a disk, in Fig. 1.

In Fig. 1, the numeral 4 designates a recording surface which is preferably in the form of a paper disk. This surface is di-

vided by both "time of day lines" 5 and "speed per mile lines" 6, the former being radially disposed while the latter are in concentric relation.

The numeral 7 designates a pen or other marker for the surface 4, said marker being normally disposed at or near the innermost of the "speed per mile lines" 6, as shown in Fig. 1. Connected with this marker in any desired manner, is electro-magnetic means 8 which functions to normally hold said marker at the position above mentioned, and also serves to return it to said position, after it has been moved therefrom. Also connected to the marker 7 in any desired manner, I have shown operating means 9 of a nature to move the marker 7 across the "miles per hour lines" 6, as soon as the electro-magnetic means 8 is released, and said operating means 9 is of such nature that it will move the marker at a predetermined, uniform rate of speed, toward the lowest speed line, as long as a predetermined portion of a train is upon a selected block (A—B) of a railway R. As soon as said predetermined portion of the train however runs from the block A—B into the block B—C, provision is made for again energizing the electro-magnetic means 8, so that the marker 7 is immediately returned to its initial position, and the maximum movements of this marker in either direction, may be controlled by appropriate stops.

In the construction herein disclosed, the marker 7 is mounted on a rod 10 which is slideable in a pair of guides 11, and the electro-magnetic means 8 includes a solenoid coil 12 and a core 13, the latter being secured to the rod 10. The operating means 9 for the marker 7, in the present showing, includes a chain 14 or its equivalent, connected to the end of the rod 10 remote from the core 13, said chain passing over a wheel 15 and being provided with a weight 16, which weight is supported as long as the electro-magnetic means 8 is energized, but is released when said means is de-energized, so that the weight will then descend by gravity. Any desired governing means, such as a clock mechanism 17 may be associated with the wheel 15 so as to insure that the weight 16 shall descend only at the predetermined and uniform speed which is to be imparted to the marker 7.

While in some instances, the means 8 might be relied upon to both return the

marker 7 to its initial position and to elevate the weight 16 to its normal position and hold these parts 7 and 16, I prefer to provide additional means such as a motor, a 5 solenoid, or the like, which acts to raise the weight 16 and hold it, so that the means 8 need not perform this double function. In the present disclosure, a solenoid core 18 is shown connected with the weight 16 and sur- 10 rounded by a solenoid coil 19, and this coil and the coil 12 are in the same circuit. An adequate circuit has been illustrated but any other desired circuit could of course be used. In connection with this circuit, 20 designates 15 a source of current supply of any desired form. Leading from this source, is a wire 21 which is connected with one end of the coil 12 and with one end of the coil 19. Another wire 22 is shown connected with the 20 other ends of these two coils and leads to a stationary contact 23 which is normally engaged by a switch 24, this switch being connected by a wire 25 with the source 20. By this or equivalent wiring, the switch 24 being normally closed, the circuit for the coils 12 and 19 is complete, so that they hold the marker 7 and the weight 16 at initial position, as shown in Fig. 1.

In the present showing, the switch 24 is 30 held normally closed by a relay 26 having a switch 27 which is co-operable with a contact 28 for controlling an ordinary block signal. The circuit of the relay 26 is a track circuit formed in part by the rails of block 35 A-B and in part by a track battery 29, and as this circuit is normally closed, the switch 24 will remain closed. As soon as the front wheels of a train however, enter the block A-B, proceeding toward the block B-C, 40 said front wheels and the axle will shunt the current of the track battery 29 from the relay 26, thus allowing the switch 24 to open at the same time the switch 27 opens, and as soon as opening of said switch 24 takes 45 place, the coils 12 and 19 are de-energized, with the result that the marker 7 immediately starts to proceed across the "miles per hour lines" 6, at the predetermined uniform speed. This proceeding of the marker takes place as long as the front wheels of 50 the train are upon the block A-B, and provision is made for immediately returning said marker to its initial position, as soon as the front wheels of the train leave said block 55 A-B. In the present showing, this means is controlled by a relay 26' for the block B-C, said relay being controlled in the same manner as the relay 26. 27' designates the signal-controlling switch of this relay, 60 and 24' has reference to an added switch which is normally held open by said relay. One end of this switch is shown connected by a wire 30 with the source 20 while its other end is co-operable with and normally 65 spaced from a contact 31, the latter being

connected by a wire 32 with the wire 22. Just as soon as the front wheels of a train enter the block B-C from the block A-B, the current from the relay 26' is shunted through said front wheels and the front axle, 70 with the result that the switch 24' closes at the same time the signal-controlling switch 27' opens. Upon closing of switch 24', current flows through the wire 21 to the coils 12 and 19, returns from these coils through the wire 22 and the wire 32 to the contact 31, and from this contact returns to the source 20, through the switch 24' and the wire 30. The circuits of the two coils being thus completed, they immediately function to return 75 the marker 7 and the weight 16 to their initial positions.

Provision is made for moving the recording surface 4 so as to successively present its "time of day lines" 5 to the marker 7, a 80 table 33, driven and controlled by a clock mechanism 34, being provided for this purpose, the arrangement and timing being of course such that at 1 a. m., the 1 a. m. line 5 will be presented to the marker 7, by the 85 time 2 a. m. arrives, the 2 a. m. line will be positioned at said marker, etc. Thus, any time the marker 7 starts outwardly, the inner end of the line which it makes, shows 90 distinctly the time of day at which the front end of a train enters the block A-B. Throughout the entire time, the front end of the train is upon this block, the marker 7 is moving at its predetermined uniform 95 rate of speed, across the "miles per hour 100 lines" 6, from the highest speed line thereof toward the lowest speed line, and it will be recalled that as soon as the front end of the train leaves the block A-B, this marker is quickly returned to its initial position. 105 the marker 7, it will thus be seen, moves outwardly only during the interval while the predetermined portion of the train is traversing the block A-B, and if during 110 this movement of the train, the marker 7 has time only to move to the "sixty mile per hour line," it is recorded that the train was making this speed when it traversed the block A-B. If the train is going slower, 115 the marker 7 moves outwardly for a greater length of time and if the train was making say thirty miles per hour, the marker 7 has progressed outwardly until it reaches the "thirty mile per hour line" before it is returned to its initial position. Thus, it will 120 be seen that the average speed of trains may be easily and accurately recorded, as well as giving the exact time of day which any train entered the block A-B and left said block. It will be understood that the lines 125 6 are provided with "speed per mile designations" but such designations have been omitted from the drawing.

In Fig. 3, a marker 7^a controlled in the same manner as the marker 7 is shown, co- 130

operating with a recording tape 4^a which, by a suitable clock mechanism, is unwound from one roller 35 and wound onto another roller 36. This tape is provided with transverse "time of day lines" 5^a, and with longitudinal "miles per hour lines" 6^a, the operation of this form of construction being the same as that above described.

From the foregoing, taken in connection with the accompanying drawing, it will be seen that simple, inexpensive, efficient and accurate means have been provided for recording in miles per hour, the average speed of all trains moving over a predetermined block, and while excellent results may be obtained from the general association herein disclosed, it is to be understood that within the scope of the invention as claimed, various modifications may be made. Moreover, the expression "miles per hour lines" is not to be considered as limiting, as these lines might in some instances represent other distances per unit of time.

I claim:—

1. A means for recording in miles per hour the average speed of a train over a block of trackage, said means comprising a record surface divided by both "time of day lines" and "miles per hour lines," one set of lines crossing the other set, a marker for said record surface mounted for movement across said "miles per hour lines," means for moving said record surface at a uniform speed in a direction to successively present its "time of day lines" to said marker, train-controlled means for moving said marker from an initial position across said "speed per mile lines" toward the slowest speed line thereof at a predetermined uniform rate of speed as long as a predetermined portion of a train is upon the block, and means for then automatically returning said marker to said initial position.

2. A means for recording in miles per hour the average speed of a train over a block of trackage, said means comprising a record surface divided by both "time of day lines" and "miles per hour lines," one set of lines crossing the other set, a marker for said record surface mounted for movement across said "miles per hour lines," means for moving said record surface at a uniform speed in a direction to successively present its "time of day lines" to said marker, electro-magnetic means for normally holding said marker at an initial position and returning it to such position after movement therefrom, normally idle means for moving said marker at a predetermined uniform speed across said "miles per hour lines" toward slowest speed line thereof when said electro-magnetic means is de-energized, a circuit for said electro-magnetic means including a normally closed switch, train-controlled means for opening said switch when

a predetermined portion of a train enters the block, thereby effecting starting of the marker across the "miles per hour lines," and means for again closing a circuit through said electro-magnetic means when said predetermined portion of the train has left the block, thereby returning said marker to said initial position.

3. A means for recording in miles per hour the average speed of a train over a block of trackage, said means comprising a record surface divided by both "time of day lines" and "miles per hour lines," one set of lines crossing the other set, a marker for said record surface mounted for movement across said "miles per hour lines," means for moving said record surface at a uniform speed in a direction to successively present its "time of day lines" to said marker, electro-magnetic means for normally holding said marker at an initial position and returning it to such position after movement therefrom, normally idle means for moving said marker at a predetermined uniform speed across said "miles per hour lines" toward the slowest speed line thereof when said electro-magnetic means is de-energized, a circuit for said electro-magnetic means including a normally closed switch, train-controlled means for opening said switch when a predetermined portion of a train enters the block, thereby effecting starting of the marker across the "miles per hour lines," and means for again closing a circuit through said electro-magnetic means when said predetermined portion of the train has left the block, thereby returning said marker to said initial position, said last named means including a normally open switch associated with the next block of the trackage, and train-controlled means for effecting closing of this switch.

4. A means for recording in miles per hour the average speed of a train over a block of trackage, said means comprising a record surface divided by both "time of day lines" and "miles per hour lines," one set of lines crossing the other set, a marker for said record surface mounted for movement across said "miles per hour lines," means for moving said record surface at a uniform speed in a direction to successively present its "time of day lines" to said marker, electro-magnetic means for normally holding said marker at an initial position and returning it to such position after movement therefrom, normally idle means for moving said marker at a predetermined uniform speed across said "miles per hour lines" toward the slowest speed line thereof when said electro-magnetic means is de-energized, a circuit for said electro-magnetic means including a switch, electro-magnetic means for holding said switch normally closed, a normally closed track circuit for

- the last named electro-magnetic means whose current supply is thrown out of play by the front wheels and axle of a train entering the block, thereby opening said 5 switch and de-energizing the first named electro-magnetic means, a second switch for a circuit through the first named electro-magnetic means for holding said second switch normally open, and a normally closed 10 track circuit for the last named electro-magnetic means whose current supply is thrown out of play by said front wheels and axle upon passage thereof from the block, permitting closing of said second switch.
5. In a device having a block of trackage 15 with track circuit and relay controlled by said circuit; electrically-controlled average speed recording means for trains passing over said block, and switch means controlled by said relay for bringing said recording means immediately into play when the front wheels of a train enter said block and for throwing said recording means immediately 20 out of play when said wheels leave the block.
- 25 In testimony whereof I have hereunto affixed my signature.

THOMAS R. MILLS.
